DESIGN FOR A COMBINED WASHING MACHINE CASING AND WRINGER

Fred C. Schwaneke, Jr., Kansas City, Mo.,
assignor, by mesne assignments, to The
Apex Electrical Manufacturing Com-
pany, Cleveland, Ohio, a corporation of
Ohio

Application June 1, 1936, Serial No. 62,926

Term of patent 7 years

To all whom it may concern:

Be it known that I, Fred C. Schwaneke, Jr., a citizen of the United States, residing at Kansas City, Jackson County, Missouri, have invented a new, original, and ornamental Design for a Combined Washing Machine Casing and Wringer, of which the following is a specification, reference being had to the accompanying drawings, forming part thereof.

In the drawings:

Fig. 1 is a perspective view of one side of a combined washing machine casing and wringer showing my new design, the characteristic fea-

tures of which are the tub casing having the annular ribs arranged on opposite sides of plated bands together with the configuration of the supporting legs including the rib-like portions extending in relief from the surfaces of the legs.

Figure 2 is a perspective view of the opposite side of the combined washing machine casing and wringer.

I claim:

The ornamental design for a combined washing machine casing and wringer, as shown and described.
